UNITED STATES PATENT OFFICE.

SAMUEL L. McBRIDE, OF ATLANTA, GEORGIA.

WATER COOLER AND FILTER.

SPECIFICATION forming part of Letters Patent No. 268,257, dated November 28, 1882.

Application filed May 3, 1882. (No model.)

To all whom it may concern:

Be it known that I, SAMUEL L. McBRIDE, a citizen of the United States, and a resident of Atlanta, in the county of Fulton and State of Georgia, have invented a new and valuable Improvement in Water Coolers and Filters; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a vertical sectional view of my filter and water-cooler. Fig. 2 is a horizontal sectional view of the same, and Fig. 3 is a cross-sectional view.

This invention has relation to water-cooling devices as well as to water-filters; and it consists in the construction and novel arrangement of the water-chamber, having vertical branches at each end of the ice-chamber, and a horizontal portion under the ice-chamber communicating with said vertical branches, the ice-chamber being independent of the water-chamber. The invention also consists in making one of the upright branches of the water-chamber higher than the other, and providing a filtering-partition to act on the water as it passes from the receiving portion of the chamber to that part from which it is to be drawn for use; and the invention finally consists in providing, in connection with the cooler or vessel, a reversible filter-containing cylinder or chute, all as hereinafter set forth.

In the accompanying drawings, the letter A designates the body of the vessel, which is of elongated form, flat from side to side, and at one end is provided with a raised portion, being the upper end of one of the vertical branches of the water-chamber.

B indicates the ice-compartment, which is placed between the vertical branches C and C' of the water-chamber, and over the horizontal portion D of said water-chamber. On each side of the ice-compartment is an air-space, a, between the side wall of the vessel and the wall of said compartment. The ice-compartment B is provided with a draw-off cock, b, and the water-chamber with a faucet, c. A

cleaning-aperture, d, is arranged at one end of the horizontal portion of the water-chamber, and is closed by a plug or screw-cap, as indicated at e. The vertical branches C and C' are provided with covers, E, and the intermediate ice-compartment with an independent cover, F, as shown in the drawings.

When it is desired to provide a filter a stone filtering-partition, f, is arranged across either of the vertical branches of the water-chamber. It is preferred, however, to make the longer vertical branch, C, detachable from the main vessel, providing it with shouldered or tapering end walls, g, of similar form, adapted to fit the same seat, h, of the main vessel. In order to render the joint water-tight, it may be packed with a rubber gasket. The filter-stone f is arranged midway between the ends of the branch or chute C, which, when constructed in the manner set forth, is readily reversed. It is designed in using this device to reverse the chute C from day to day, so as to filter in opposite directions through the stone at different times, thereby keeping the stone clean; or the filter-stone may be arranged vertically across the horizontal portion of the water-chamber; or it may be located at the lower end of the shorter branch of the water-chamber, and the water, poured in through the longer branch, allowed to filter upward through said stone into the shorter branch.

Sometimes it may be preferable to use other filtering material instead of stone in constructing the filtering partition.

Having described this invention, what I claim, and desire to secure by Letters Patent, is—

1. The water-cooler described, having vertical branches of the water-chamber at each end of the ice-compartment, and a horizontal portion of the water-chamber below said compartment communicating with the vertical branches, and the air-spaces on each side of the ice-compartment, substantially as specified.

2. The water-cooler described, having vertical branches C C' of the water-chamber, of different heights, at each end of the ice-compartment, and a horizontal portion, D, of said chamber below said compartment, substantially as specified.

3. In a water-cooler having an independent

middle ice-compartment, and a water-chamber having vertical branches of different heights, and a horizontal portion under said ice-compartment connecting said branches, a filtering-partition, *f*, substantially as specified.

4. In a water-cooler, the detachable and reversible cylinder or chute *C*, having a filter-partition, *f*, and open ends *g*, similarly shouldered, tapered, or finished to engage the seat of the main vessel, substantially as specified.

In testimony that I claim the above I have hereunto subscribed my name in the presence of two witnesses.

SAMUEL L. McBRIDE.
